UNITED STATES PATENT OFFICE.

CHARLES ROSENBLUM, OF NEW YORK, N. Y.

SUITCASE SNAP-BOLT.

1,186,336.

Specification of Letters Patent. Patented June 6, 1916.

Application filed August 18, 1915. Serial No. 46,075.

To all whom it may concern:

Be it known that I, CHARLES ROSENBLUM, a citizen of the United States, and a resident of the city of New York, borough of Manhattan, in the county and State of New York, have invented a new and Improved Suitcase Snap-Bolt, of which the following is a full, clear, and exact description.

This invention relates to temporary hasps or fasteners for receptacles and is adapted especially for travelers' suitcases or the like.

Among the objects of the invention is to construct a fastener or hasp comprising a stud for attachment to one part of the receptacle and a tongue part carried by another part of the receptacle movable relatively to the first part mentioned and cooperating with said stud, a peculiar form of spring being provided to make the co-operation between the stud and tongue more secure.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a perspective view of a portion of a receptacle having one form of my invention applied thereto; Fig. 2 is a vertical sectional view of the same on the line 2—2 of Fig. 1; and Fig. 3 is a detail view indicating the form of the spring and the cup for securing it in position.

Referring now more particularly to the drawings, I show a receptacle which may be regarded as a suitcase 10 having a relatively movable top lid 11. The fastener comprises a stud 12 carried by a plate 13 secured rigidly and permanently as by rivets 14 or their equivalent to the main part of the receptacle. The other main portion of the fastener comprises a tongue or plate 15 carried by a plate 16 secured firmly as by rivets or the like to the cover 11. The tongue may be hinged as indicated at 18, if desired, to facilitate the action thereof with respect to the stud. The base 13 and the tongue may be provided with circumferential ribs, as indicated at 19 and 20 respectively, to stiffen and strengthen the same. That portion 21

of the tongue within the rib 20 is flat and lies closely against the outer face of the base 13 and is provided with a central hole concentric with both of the ribs through which 60 the stud projects.

The numeral 23 indicates a cup having a series of spurs 24 projecting inwardly from the rim thereof through correspondingly formed holes in the plate 21. The outer face 65 of the cup is flat and provided with a central hole 25 through which the stud projects, the hole being substantially of the same diameter as the head of the stud. This cup 23 constitutes a holder for a spring 26 70 in the form of an equilateral triangle, each side of which spans a portion of the hole 25 as noted in Fig. 3; thereby the spring bears upon the stud 12 at three different points. The spring may be made at very low cost 75 and the assemblage of the parts may be effected with facility. The cup 23 with its flat face and circular rim retains the spring in operative position but permits free rotation or floating thereof around the axis of the 80 hole 25. This free rotation or floating action of the spring around the axis of the stud provides not only an easier action of the fastener in locking or unlocking, but also serves to distribute the wear between it 85 and the stud to all parts of the stud's surface. The tongue member may be provided with a downwardly and outwardly projecting lip 27 to facilitate the disconnection of the two main parts. 90

The main strain resisting the opening movement of the lid 11 is borne directly between the tongue or plate member 15 and the rigid stud, the spring serving only to prevent the outward movement of the tongue or displacement from the stud. While the force of the spring is sufficient to prevent this accidental separation of the parts, it is not so great as to render the device difficult to open in its intended way, by application of the 100 force of a finger to the lip 27. 95

I claim:

1. The combination with the main part of a receptacle and a relatively movable part thereof, of a fastener comprising a base 105 plate secured to one of the receptacle parts, a rigid stud carried by the base plate, a tongue member carried by the other receptacle part and having a hole adapted to receive said stud, a cup secured to the tongue 110 and comprising a flat outer face and a circular rim, said cup face having a hole in aline-

ment with the tongue hole, and a straight-sided spring carried within the tongue cup and intersecting a plurality of portions of the hole providing a similar number of holding contact points preventing separation of the tongue from the stud, said spring being rotatable within the cup freely around the axis of the stud.

2. A fastener of the character set forth comprising a base, a rigid stud carried by the base, a plate member having a hole adapted to receive said stud, a cup secured to the plate member and comprising a flat outer face and a circular rim, said cup face

having a hole in alignment with the plate 15 hole, means to secure the cup rim to the plate, and an equilateral triangularly shaped spring carried within the cup and intersecting three portions of the aligned holes providing a like number of holding contact 20 points preventing separation of the plate from the stud, said spring being rotatable within the cup freely around the axis of the stud.

CHARLES ROSENBLUM.
